(57) **CLAIM**

The ornamental design for cover plate for electrical devices, as shown and described.

DESCRIPTION

FIG. 1 is a top, front, side perspective view of a cover plate for electrical devices showing my new design;

FIG. 2 is a front elevational view thereof;

FIG. 3 is a rear elevational view thereof;

FIG. 4 is a top plan view thereof;

FIG. 5 is a bottom plan view thereof;

FIG. 6 is a left side elevational view thereof; and,

FIG. 7 is a right side elevational view thereof.

1 Claim, 3 Drawing Sheets---
